W. F. RUNDELL.
LIFTING JACK.

No. 37,707.

Patented Feb. 17, 1863.

UNITED STATES PATENT OFFICE.

WILLIAM F. RUNDELL, OF EAST GENOA, NEW YORK.

IMPROVEMENT IN LIFTING-JACKS.

Specification forming part of Letters Patent No. 37,707, dated February 17, 1863.

To all whom it may concern:

Be it known that I, WILLIAM F. RUNDELL, of East Genoa, in the county of Cayuga and State of New York, have invented a new and Improved Jack for Elevating Carriages; and I do hereby declare that the following is a full and exact description thereof, reference being had to the accompanying drawings, making a part of this specification, in which—

Figure 1 is a perspective view of my invention, and Fig. 2 is a side elevation of a portion of the lever and fulcrum-pin.

Similar letters of reference indicate corresponding parts in the two figures.

To enable others skilled in the art to make and use my invention, I will proceed to describe its construction and operation.

I use for a base a block of wood or other firm material, for ordinary purposes, the most convenient dimensions of which are twelve inches long, six inches wide, and two inches thick. In the center of the base I erect a standard, *d*, of wood or other firm material, and permanently fixed to the base by mortise or otherwise, and standing in a position slightly inclining or leaning toward one end of the base, by which inclination of the standard the weight which rests upon the jack when operating is brought to bear directly upon the center of the base, and thereby prevents tipping. The dimensions of a standard most convenient for ordinary use are two feet in length, four inches in width, and two inches in thickness. The upper half of the standard I divide into three equal parts by running lines lengthwise thereof. I remove the inner part, leaving the two outer parts, which form two distinct pillars. I provide two rack-bars, *g g*, of iron or other metal, each being one foot in length. Each rack-bar has upon its side a number of teeth, for the purpose of suiting the operation of the jack to any required degree of height. Each rack-bar corresponds with the other in the number, form, and size of the teeth. To each one of the aforesaid pillars, and upon that side of the standard forming an obtuse angle with the base, I firmly affix by screws or otherwise a rack-bar, *g*, with the teeth pointing outward and upward, as clearly shown in the drawings. An iron or steel tooth-rack, *e*, with the teeth pointing downward, I attach to the standard, and upon that side forming an acute angle with the base, and so arrange it that the points

of the teeth are parallel and in range with the inner side of one of the pillars, and at a distance therefrom of five inches or thereabout. The horizontal piece of the rack-bar at top, and by which it is attached to the standard, besides serving the purpose of attaching the rack to the standard, forms a handle by which the jack can be conveniently carried about. I construct a lever, *c*, of a curved shape, which curved shape gives it great superiority over the straight lever in operating under carriages having their bodies located immediately upon or near to the axle-tree, and extending out a few feet beyond it. The upper side of the lever at *b* I cut away in an oval form, by which means it gradually changes its point of contact with the axle-tree by rolling, and raises it perpendicularly, thereby preventing the axle-tree from sliding upon the lever. In the center of the oval form I make a small square niche to suit the iron axle-trees of buggy-wagons.

m is a feathered-edge plate, secured by screws or otherwise to the upper side of the lever, and adapted to engage with the teeth of the rack *e*, to secure the lever at any desired height when subjected to strain on its short end. Passing loosely through the lever at six inches or thereabout from the end is an iron fulcrum-pin, *a*, which is secured to its place by a setscrew, *n*, which passes perpendicularly through the lever from the under side. The fulcrum-pin is fitted loosely in the lever for the purpose of allowing the latter to be vibrated or moved laterally upon the pin, thereby preventing the springing of the standards or bending of the lever in shifting its feathered-edge knife into the different teeth of the rack.

To operate with my invention, place the lever *c* between the pillars of the standard, with the fulcrum-pin *a* resting upon the teeth of the rack-bars *g g*. Place the end of the lever, which is cut away to an oval form, under the axle tree of a carriage, and with the hand bear down upon the other end of the lever. An iron tooth fixed to the side of the lever will slide down over the teeth of the tooth-rack *e*, and may be attached thereto at any point the operator may desire.

What I claim, and desire to secure by Letters Patent, is as follows:

1. Having the fulcrum-pin *a* fitted loosely in a hole in the lever *c*, and secured against

casual longitudinal movement therein by means of a set-screw, *n*, when arranged in the manner and for the purpose specified.

2. The rigidly-attached rack-bar *e*, standard *d*, and toothed racks *g g*, in combination with the loosely-fitted fulcrum-pin *a*, lever *c*, and feathered-edge plate *m*, when the whole is ar-

ranged to operate in the manner and for the purpose specified.

WILLIAM F. RUNDELL.
